DESIGN FOR A LIP ROUGE CONTAINER

Preston H. Scott, Montclair, N. J.

Application May 24, 1934, Serial No. 51,906

Term of patent 3½ years

To all whom it may concern:

Be it known, that, I, PRESTON H. SCOTT, a citizen of the United States, residing at Montclair, in the county of Essex and State of New Jersey, have invented a new, original, and ornamental Design for a Lip Rouge Container, of which the following is a specification, reference being had to the accompanying drawing, forming part thereof:

Fig. 1 is a perspective view of the lip rouge container;

Fig. 2 is a side elevation of the container of Fig. 1 with the cover open; and

Fig. 3 is a perspective view of the lip rouge container shown in Fig. 1 with the cover open.

I claim:

The ornamental design for a lip rouge container substantially as shown and described.

PRESTON H. SCOTT.
